ATTORNEY

UNITED STATES PATENT OFFICE

158,978

NEGLIGEE COAT OR SIMILAR ARTICLE

Sam Landau, New York, N. Y.

Application October 5, 1949, Serial No. 5,317

Term of patent 3½ years

(Cl. D3—26)

To all whom it may concern:

Be it known that I, Sam Landau, a citizen of the United States of America, residing in New York city, county of New York and State of New York, have invented a new, original, and ornamental Design for a Negligee Coat or Similar Article, of which the following is a specification, reference being had to the accompanying drawing, forming part thereof, wherein:

I claim:

The ornamental design for a negligee coat or similar article, substantially as shown.

SAM LANDAU.
